UNITED STATES PATENT OFFICE.

JOHN M. HARDIN, OF GEST, ASSIGNOR OF ONE-FOURTH TO GEORGE W. LAWRENCE, OF LOUISVILLE, KENTUCKY.

VEHICLE-BRAKE.

SPECIFICATION forming part of Letters Patent No. 464,966, dated December 15, 1891.

Application filed October 27, 1890. Serial No. 369,410. (No model.)

To all whom it may concern:

Be it known that I, JOHN M. HARDIN, a citizen of the United States, residing at Gest, in the county of Henry, State of Kentucky, have 5 invented certain new and useful Improvements in Vehicle-Brakes, of which the following is a full, clear, and exact description, reference being had to the accompanying drawings, forming part of this specification.

10 My improvement relates to brakes for vehicles in which the brake is operated by the movement of the tongue, so that they will be set when the vehicle is traveling a downgrade and released on reaching a level or upgrade, 15 and also to means for setting the brakes in case of a runaway.

My invention consists in the novel construction and arrangement of parts herein-after fully set forth, and pointed out in the 20 claims.

In the drawings, Figure 1 is a side elevation of a wagon to which my brake is attached. Fig. 2 is a top plan view of same. Fig. 3 is a vertical section of the rear portion 25 of the tongue, showing method of attaching same to hounds.

A is the tongue or pole of an ordinary two-horse wagon, which is attached to the forward hounds B B by the bolt a, passing horizontally through the same, the tongue having a longitudinal slot b to allow for a forward and backward movement of the tongue while still retaining it to the hounds. A plate C, bolted underneath the hounds, also supports the 35 tongue, so that it slides between the forward hounds and upon this plate C within the limits of the slot a.

Attached to the upper side of the rear end of the tongue A by the pin d is the bar or rod D, which is slotted at e to allow a slight play. The rod D is connected with the arm f of the lever-shaft E, which is journaled in supports F F, attached to the hounds of the wagon. The lever-shaft E is also provided with an- 45 other arm g, extending down from the shaft, so that the rotation of the rock-shaft will move the arms f and g in opposite directions. A similar brake or lever shaft H with a similar arm h extending upward and two arms i i 50 extending downward at the end of the shaft is journaled to the vehicle at the rear, and

the arm h is connected with arm g by connecting-rods k and l, which are lapped and held together by box m and set-screw n, so as to allow adjustment of the length of these 55 connecting-rods.

The brake-bar K, provided with brake-shoes L L, is hung by the chains p p from a cross-bar M, bolted to the rear hounds of the vehicle. To the front of this brake-bar are secured the loops or hooks o o, which extend downward from the brake-bar and by which the brake is connected with the arm i i by suitable rods N N, the connection between brake-bar and rod being pivoted by means of 65 the hooks rr at the ends of the rods N N. It will be seen from this construction that the moment the horses draw back on the tongue in the act of descending a hill the backward movement of the tongue will rotate lever-shafts E and H, and the brake-shoes will be 70 drawn firmly against the rear wheels, while the moment this pressure is relieved from the tongue the brake bar and shoes will be swung away from the wheels. In backing the vehicle, however, although the action on the tongue will tend to set the brakes, inasmuch as the 75 brake-bar is merely hung to the cross-bar M and pivotally connected with rods N N, the revolution of the wheels in the opposite direction will allow the brake bar and shoes to 80 swing up with the movement of the wheels out of the way, and thus it will be seen that it is only while the wheels are turning in the direction to advance the vehicle that the 85 drawing back of the tongue will set the brakes.

In order to obtain means for setting the brake in case of a runaway, I provide, further, as follows: By the same pin d which attaches bar D to the tongue the doubletree 90 P is also pivoted to the tongue, the stirrup R, bolted to the tongue, acting as a brace and support for the doubletree and pin. Above this stirrup and hinged thereto at s is a hand-lever t, and the pin d passes down 95 through this lever, the stirrup, and doubletree into a recess in the tongue, the head of the pin d being above the lever t, so that by drawing up the lever t by cord u the pin d may be drawn out, as shown by dotted lines, Fig. 100 1, and thus allowing the doubletree to be drawn forward within the limits of the stir-

rup R. The outer ends of this doubletree are attached by chains v to a supplemental arm w on lever-shaft E, so that the drawing forward of the doubletree will rotate said shaft and thus set the brakes. All that need be done in case the team should endeavor to run away is to draw the pin d, when the brakes will at once be set.

Having thus described my invention, what I claim, and desire to secure by Letters Patent, is—

1. In a vehicle-brake, the combination of the brake-shoes, the sliding tongue A, means connecting the tongue and brake-shoes, where-
15 by the brake will be set and released, respect-
ively, by the backward and forward move-
ment of the tongue, the detachable double or
whiffle tree P, means connecting the double or
whiffle tree with the brake-shoes, whereby the
20 brake will be set by the forward movement
of said tree when the tree is detached, and
means for detaching the said tree, substan-
tially as shown and described.

2. In a vehicle-brake, the brake or lever
25 shaft H and brake-shoes L, connected there-
with, the lever-shaft E, means connecting the

brake-shaft II and lever-shaft E, the slotted
movable tongue A, bolt a, rod D, detachable
double or whiffle tree P, bolt d, and lever t, en-
gaging said bolt, all constructed and com- 30
bined substantially as shown and described.

3. In a vehicle-brake, the combination, with
the brake-shoes, of the detachable double or
whiffle tree P, means connecting the tree with
the brake-shoes, whereby the brake will be 35
set by the forward movement of the tree when
said tree is detached, and means for detach-
ing the said tree, substantially as shown and
described.

4. In a vehicle-brake, the combination, with
the brake-shoes, of the detachable double or
whiffle tree P, means connecting the tree with
the brake-shoes, whereby the brake will be
set by the forward movement of the tree when
the tree is detached, the bolt d, and lever t, 40
45 engaging said bolt d, substantially as shown
and described.

JOHN M. HARDIN.
